UNITED STATES PATENT OFFICE.

BENJAMIN CARL MCCLURE, OF SCARSDALE, AND LUTHER BURCHARD McMILLAN, OF LARCHMONT, NEW YORK, ASSIGNEES TO JOHNS-MANVILLE INCORPORATED, OF NEW YORK, N. Y., A CORPORATION OF NEW YORK.

HEAT-EXCHANGE DEVICE.

Application filed July 31, 1922. Serial No. 578,580.

This invention relates to heat exchange or economizer devices in which the heat of one fluid is imparted to another fluid without commingling the fluids and without actual contact of the one with the other. Devices of this character are useful in many arts where conservation or economy of heat is important; for example in connection with dryers, carbonizers and kindred apparatus used in textile and other manufacturing plants for processing and finishing materials, fabrics, and completed articles.

The objects of the invention are to provide a heat exchange device of simple and economical construction, having mutually related intertwined passages formed by the assemblage of like units of partition within a trunk or shell, in such manner that the gaseous currents in the passages repeatedly impinge upon substantially flat surfaces and are thereupon thrown into whirls and eddies which assist in effecting heat transfer from the fluid in one passage to that in another.

In order to illustrate the invention, typical species of the genus constituting the invention are shown by way of example in the accompanying drawings, in which—

Fig. 1 is a perspective view, parts being broken away to show internal structures, of a heat exchange device of one form;

Fig. 2 is a section in elevation on the line 2—2 of Fig. 1;

Fig. 3 is a section in plan on the line 3—3 of Fig. 1;

Fig. 4 is a transverse section on the line 4—4 of Fig. 2;

Fig. 5 is a perspective view of one of the unit partitions;

Fig. 6 is a perspective view similar to Fig. 1 of another form of the device;

Fig. 7 is a section in elevation of the line 7—7 of Fig. 6;

Fig. 8 is a section in plan on the line 8—8 of Fig. 6;

Fig. 9 is a transverse section on the line 9—9 of Fig. 7;

Fig. 10 is a perspective view of a unit partition used in the form of Figs. 6 to 9;

Fig. 11 is a diagram perspective view of the partition assembly of the device disclosed in Fig. 1, showing the direction of the fluid currents; and

Fig. 12 is a diagram perspective of the partition assembly of the type disclosed in

Fig. 6, showing the direction of the fluid currents.

Referring now to Figs. 1 to 5 and 11, an enclosure A having side walls 12 and 13, ends 14, top and bottom walls 15 and 16, and rectangular in cross section as indicated in Fig. 4, may be divided into a series of like cells or chambers 17, between substantially parallel partition walls extending laterally of the enclosure A formed by said walls 13, 14, 15, 16. Recurring (shown as alternate) cells or chambers 17 are connected by passageways 18^a, Figs. 2 and 3, these passageways for the alternate series of cells 17 lying along a different pair of opposite walls 15, 16, of the enclosure from the similar passages 18^b for the other intervening alternate series, which passages lie along the side walls 12, 13. Two separate and distinct fluid paths thus formed extend throughout the length of the device, one path x, indicated by arrows in Figs. 1, 2 and 11, entering and leaving the device by means of openings 19 and 20 in the ends 14, and the other y, indicated by arrows in Figs. 1, 2 and 11, entering and leaving the device through openings 21 and 22 in side walls 13 and 12 respectively at diagonally opposite points.

Such cells and passageways may be formed by installing within enclosures A, of which that shown is typical, a series of like unit partitions, preferably integral, each of which, see Fig. 5, comprises a relatively large transverse member a, a narrow longitudinal member b disposed at right angles to one edge of member a, a smaller transverse member c at right angles to the outer free edge of member b, of sufficient size to cover a rectangular area of which the height is one interior dimension of enclosure A less one dimension of member a and of which the base is the other dimension of the enclosure A, less the other dimension of member a. When assembled for installation within the enclosure each successive partition is rotated relative to the next preceding partition. In the device illustrated, each successive partition is rotated a quarter turn. Consideration of Fig. 11, which shows a partition-assembly separate from the container in which it is to be installed, will explain the relationship to each other of these partitions, which are suitably joined

to the enclosure A and to each other at their contacting edges. As best shown in Fig. 2, the joint between the walls of the enclosure A and the partitions may be any suitable 5 air- or gas-tight juncture adapted to the material of which the device is made, such as a gain or groove g to receive the edge of the partition, and a suitable coating of cement g' to seal the joint so formed. Any other 10 form of juncture between the container A and the internal partitions may be employed, for instance as referred to below.

The fluid currents x and y flowing through the device as indicated by dotted and broken 15 lines respectively in Figs. 1 to 3 and 11 are caused to take undulatory paths lying generally in opposite directions in the cellular spaces. Within these spaces the mean central path of one flow in one series of cells 20 undulates in an up and down direction, and in the other path through the other series of cells undulates horizontally. The crests of these undulations are displaced in respect to one current half a wave-length from the 25 crests of the other current. These currents thus intertwine within the general space defined by the enclosure A and are caused to impinge everywhere respectively upon opposite sides of the members a , b , c of the inner partitions, the currents in contact with the opposite sides of the partitions everywhere traveling at right angles to each other. The changes of direction are frequent, and 30 impingement against the partitions from 35 flow is occasioned at each change of direction.

The warmer and moister current flowing through the device may be expected to condense its moisture on the walls of the cells formed by the partitions a , b , c ; for instance, current x , Figs. 1 and 3, may be a warmer and moister outflow current, and current y a colder and dryer inflow current. It will be observed that the form of the cells through which current x flows is such as to 40 permit moisture to collect by gravity on the bottom wall 16 of the enclosure A. The moisture collected may be drained from this space in any suitable manner, for instance by the provision of holes h near one lower 45 corner of the device, which is positioned in practice so that this corner will be slightly lower than the remainder of the device. The drip may be carried off by pipes h' , Fig. 4, 50 from these holes.

It will now be understood that the enclosure A may be of any dimensions sufficient 55 to accommodate an area of the partitions a , b , c great enough to transfer the heat from one of the currents flowing through the device to the other. The incoming current y , Figs. 1 and 2, for instance, may be of cool, dry air and the outgoing current x may be of warm, moist air proceeding from some 60 such device as an evaporator, dryer or carbonizer. The present illustrations do not

show the connections relied upon beyond the heat-exchange device A. These connections may be pipes continuing the openings 19, 20, 21, 22, these pipes having flanges bolted to the attachment flanges 19^a, 20^a, 21^a, 22^a, etc. Any suitable arrangement which includes the enclosure A so that its passages respectively are continuations of the outgoing warm-current passages and connected in the incoming cold-current passages will correspond to the intended use of the device. 75

It is to be understood that the precise form of the unit partition above explained is typical only of many forms by which the interior space of an enclosure A' may be 80 divided into series of cells, establishing flow paths through the walls of which a warm current and a cold current can exchange their heat. For one instance only of the 85 many variations within the invention, Figs. 6 to 10 inclusive, illustrate a variation of the partition walls adapted to cause the currents of one series of cells to intertwine with the currents of the other series of cells in three-dimensional spirals, as diagrammed in Fig. 12 in perspective, the current in each series of cells impinging upon a laterally extending wall of the partition, thence moving laterally to the left into another cell, thence downward into another 90 cell, and then upward into another cell, etc.

In order to divide the space of the enclosure shown in Fig. 6 at A' for the effect indicated in Fig. 12, a unit partition shown in Fig. 10 may be repeated in assembly with the interior walls of the enclosure A', each successive unit contacting with the next, as shown in Figs. 6-9, in a position rotated a quarter-turn from that of the next partition. The unit partition shown in Fig. 10 comprises a transverse portion d , an integral transverse portion e , and an integral transverse portion f , the portion f having rectangular dimensions corresponding to the difference between the interior dimensions 100 respectively of the enclosure A' less the respective dimensions of the portion b . The longitudinal width of the cells formed by repetitions of the partition shown in Fig. 10 is determined by the longitudinal dimension 105 of the portion e , which is of sufficient height to define the full interior dimension 110 of the enclosure A'. 115

As in the case of the form above described, any suitable juncture between the edges of the unit partitions and the interior wall of the enclosure may be adopted. As best shown in Figs. 6 and 7, for instance, seats for the edges of the partitions may be 120 formed by angle strips k suitably attached to the inner walls of the enclosure A'. These strips may be cemented or otherwise fastened in place. The meeting joints k' between the respective partitions, see Figs. 125 7 and 8, may also be cemented joints. 130

By reference to Figs. 6 and 12 the internal paths of a current y entering through the opening 36 and leaving through the opening 37, and of the exit current x entering through the opening 38 and leaving through the opening 39, will be apparent.

In either of the forms above explained, the unit partition is impinged upon by the respective currents, and constitutes a septum of a medium through which the current of a higher temperature warms the current of a lower temperature.

It will now be understood that economizer or heat-exchange enclosures such as those typified by the enclosures A or A', and the partitions by which these enclosures are divided into series of cells, may vary in construction within wide limits, but we prefer constructions in which the partitions are, first, of like form, and second, of such simplicity of form as to permit making by molding or bending while plastic. The illustrated forms are adapted to be made of sheet material by blanking and bending operations well adapted to be carried out on thin sheets of the preferred fume-resistant materials. These preferred materials comprise inert mineral substances of water-resistant, acid proof quality, but we are not to be understood as excluding metallic structures, since the constructions by which the enclosures are divided into cells are advantageous to efficient heat-exchange between air, gas or vapor currents without respect to the material of which the cell walls may be composed.

One preferred material for the partitions and walls of the device is an aggregate of asbestos and a binder known to commerce as "asbestos wood", and typically consisting of asbestos and Portland cement, with or without an oleaginous impregnation. Such material, glass, some forms of porcelain and earthen-ware, thin sheets of suitable metal which may or may not be galvanized, plated, enameled or coated with adherent coats of such substances as asbestos and a cement, all lend themselves to utilization for the unit partitions above described as well as for the enclosure in which the partitions are erected to constitute the cellular structure. The entire structure shown and described may, if desired, be surrounded by a heat-insulating lagging or casing, not shown, or may be

erected within one of the hot chambers of the apparatus with which it is used.

The forms illustrated are such as are preferred to be employed when the material of the outer walls and the piping is asbestos wood.

While the constructions described have been described as made by assembly, it will be clearly understood by those skilled in the art that equivalent structures might well be molded by suitable processes, either in a single piece, or in mating halves or other fractions with integral partition structures including the structure of the interior cells, and it is within our invention to construct the apparatus in such units or partial units.

We claim:—

1. A heat exchange device comprising a shell, and having therein a series of unit partitions each partition comprising a plurality of parts disposed in angular relationship to each other, each successive partition being rotated a portion of a circumference relative to the preceding partition, whereby a plurality of tortuous passageways separated by said partitions are provided.

2. In combination, in a heat exchange device, a hollow enclosure and a series of like partitions each characterized by a transverse and a longitudinal member, whereby assembly of said partitions in mutually different rotative positions in mutual contact within said enclosure provides a series of transverse divisions of the internal space, recurrent divisions being connected in series by passageways divided from the intervening divisions of the internal space by said longitudinal members.

3. A partition for use in an enclosure of polygonal internal cross-section and adapted for heat exchange use, said partition having a transverse member adapted for edge contact with walls of the enclosure in any of several rotative positions, and an integral longitudinal member adapted to contact with an adjacent similar partition, and thereby to divide off a portion of the internal space of the enclosure in a longitudinal sense.

Signed by us at New York city, N. Y., this 18th day of July, 1922.
